[57] CLAIM

The ornamental design for a loose leaf binder, as shown and described.

DESCRIPTION

FIG. 1 is a perspective view of a closed binder embodying my design;

FIG. 2 is a front elevational view thereof;

FIG. 3 is a back elevational view thereof;

FIG. 4 is a left elevational view thereof;

FIG. 5 is a right elevational view thereof;

FIG. 6 is a bottom plan view thereof;

FIG. 7 is a top plan view thereof;

FIG. 8 is a front elevational view thereof, in a fully opened position;

FIG. 9 is a back elevational view thereof;

FIG. 10 is an enlarged view of a portion of the loose leaf binder showing the texture of the material, it being understood that the pattern is common to all embodiments of my design; and,

FIG. 11 is an enlarged cross-sectional view along line 11—11 in FIG. 10.

For the sake of clarity, FIG. 11 only depicts the profiles of the texture nubs directly along line 11—11.
